(57) **CLAIM**

The ornamental design for a mitten-shaped pouch with side pour squeeze spout, as shown and described.

DESCRIPTION

FIG. 1 is a front perspective view of a mitten-shaped pouch with side pour squeeze spout showing a first embodiment of my new design;

FIG. 2 is a front elevation of the mitten-shaped pouch with side pour squeeze spout of FIG. 1, wherein a rear elevation is a mirror image of FIG. 2;

FIG. 3 is a right side elevation of the mitten-shaped pouch with side pour squeeze spout of FIG. 1;

FIG. 4 is a left side elevation of the mitten-shaped pouch with side pour squeeze spout of FIG. 1;

FIG. 5 is a top plan view of the mitten-shaped pouch with side pour squeeze spout of FIG. 1;

FIG. 6 is a bottom plan view of the mitten-shaped pouch with side pour squeeze spout of FIG. 1;

FIG. 7 is a front perspective view of a mitten-shaped pouch with side pour squeeze spout showing a second embodiment of my new design with a portion for hanging;

FIG. 8 is a front elevation of the mitten-shaped pouch with side pour squeeze spout of FIG. 7, wherein a rear elevation is a mirror image of FIG. 8;

FIG. 9 is a right side elevation of the mitten-shaped pouch with side pour squeeze spout of FIG. 7;

FIG. 10 is a left side elevation of the mitten-shaped pouch with side pour squeeze spout of FIG. 7;

FIG. 11 is a top plan view of the mitten-shaped pouch with side pour squeeze spout of FIG. 7;

FIG. 12 is a bottom plan view of the mitten-shaped pouch with side pour squeeze spout of FIG. 7;

FIG. 13 is a front perspective view of a mitten-shaped pouch with side pour squeeze spout showing a third embodiment of my new design;

FIG. 14 is a front elevation of the mitten-shaped pouch with side pour squeeze spout of FIG. 13, wherein a rear elevation is a mirror image of FIG. 14;

FIG. 15 is a right side elevation of the mitten-shaped pouch with side pour squeeze spout of FIG. 13;

FIG. 16 is a left side elevation of the mitten-shaped pouch with side pour squeeze spout of FIG. 13;

FIG. 17 is a top plan view of the mitten-shaped pouch with side pour squeeze spout of FIG. 13;

FIG. 18 is a bottom plan view of the mitten-shaped pouch with side pour squeeze spout of FIG. 13;

FIG. 19 is a front perspective view of a mitten-shaped pouch with side pour squeeze spout showing a fourth embodiment of my new design with a wide bottom;

(Continued)

FIG. 20 is a front elevation of the mitten-shaped pouch with side pour squeeze spout of FIG. 19, wherein a rear elevation is a mirror image of FIG. 20;
FIG. 21 is a right side elevation of the mitten-shaped pouch with side pour squeeze spout of FIG. 19;
FIG. 22 is a left side elevation of the mitten-shaped pouch with side pour squeeze spout of FIG. 19;
FIG. 23 is a top plan view of the mitten-shaped pouch with side pour squeeze spout of FIG. 19;
FIG. 24 is a bottom plan view of the mitten-shaped pouch with side pour squeeze spout of FIG. 19;
FIG. 25 is a front perspective view of a mitten-shaped pouch with side pour squeeze spout showing a fifth embodiment of my new design;
FIG. 26 is a front elevation of the mitten-shaped pouch with side pour squeeze spout of FIG. 25, wherein a rear elevation is a mirror image of FIG. 26;
FIG. 27 is a right side elevation of the mitten-shaped pouch with side pour squeeze spout of FIG. 25;
FIG. 28 is a left side elevation of the mitten-shaped pouch with side pour squeeze spout of FIG. 25;
FIG. 29 is a top plan view of the mitten-shaped pouch with side pour squeeze spout of FIG. 25;
FIG. 30 is a bottom plan view of the mitten-shaped pouch with side pour squeeze spout of FIG. 25;
FIG. 31 is a front perspective view of a mitten-shaped pouch with side pour squeeze spout showing a sixth embodiment of my new design with an elongated and wide bottom;
FIG. 32 is a front elevation of the mitten-shaped pouch with side pour squeeze spout of FIG. 31, wherein a rear elevation is a mirror image of FIG. 32;
FIG. 33 is a right side elevation of the mitten-shaped pouch with side pour squeeze spout of FIG. 31;

FIG. 34 is a left side elevation of the mitten-shaped pouch with side pour squeeze spout of FIG. 31;
FIG. 35 is a top plan view of the mitten-shaped pouch with side pour squeeze spout of FIG. 31; and,
FIG. 36 is a bottom plan view of the mitten-shaped pouch with side pour squeeze spout of FIG. 31.
In the drawings, broken lines and dash-dot lines form no part of the claimed design.
